CLAIM

The ornamental design for a spring arm assembly for a weight distributing hitch, as shown and described.

DESCRIPTION

FIG. 1 is a top, front perspective view of a spring arm assembly for a weight distributing hitch;

FIG. 2 is a bottom, rear perspective view thereof;

FIG. 3 is a top plan view thereof;

FIG. 4 is a bottom plan view thereof;

FIG. 5 is a front, elevational view thereof;

FIG. 6 is a rear, elevational view thereof;

FIG. 7 is a right-side, elevational view thereof; and,

FIG. 8 is a left-side, elevational view thereof.

The broken lines shown in the drawings illustrate portions of the spring arm assembly that form no part of the claim.
